COMBINATION LAWN TRIMMER AND EDGER

Thomas C. Abrahamsen, Cherry Hill, N.J., and Harper Landell, Fort Washington, Pa., assignors to The Black and Decker Manufacturing Company, Towson, Md., a corporation of Maryland

Filed Nov. 20, 1964, Ser. No. 82,715

Term of patent 14 years

(Cl. D40—1)

FIG. 4FIG. 5FIG. 6FIG. 1 is a perspective view of a combination lawn trimmer and edger showing our new design, with the tubular handle broken away to indicate indeterminate length;

FIG. 2 is a left side elevation taken at an enlarged scale with the tubular handle fragmentarily shown for convenience of illustration;

FIGURE 3 is a right side elevation;

FIGURE 4 is a top plan view;

FIGURE 5 is a rear elevation; and

FIGURE 6 is a front elevation.

The dominant features of our design reside in the portion shown in full lines.

We claim:

The ornamental design for a combination lawn trimmer and edger, as shown and described.
